UNITED STATES PATENT OFFICE.

PETER S. SINCLAIR, OF HOLYOKE, MASSACHUSETTS.

BURNER FOR HOT-WATER HEATERS.

Application filed May 8, 1923, Serial No. 637,478. Renewed September 22, 1926.

This invention relates to improvements in oil burners for hot water heaters of the type in which a water heating member or element is provided for receiving the cold water from the city mains and discharging the same in a heated condition therefrom and into a hot water receiving or storage tank, which tanks are usually located in convenient relation to the heater. The invention 10 in particular relates to the construction and manner of mounting the oil burner, whereby the same may be swung outward in a horizontal plane and clear of the enclosing casing in which the water heating element is contained, when it is desired to adjust, or clean 15 the burner. The type of burner employed is that known in the trade as the "blue flame" oil burner. The invention in general therefore, is confined to the manner of 20 mounting the burner so that it may be swung outward or away from the enclosing casing.

Referring to the drawings:

Fig. 1 is an elevational view of the 25 closing casing having water heating elements located therein and with the door of the same shown in the open position and also showing the manner of pivotally mounting the burner on the casing.

Fig. 2 is a horizontal sectional view on the 30 line 2—2 of Fig. 1 showing the plate for supporting the oil burner and which is formed with an arc-shaped groove therein, a pipe for supporting the oil supply tank and 35 a burner supporting device on the oil supply pipe located for movement in the groove.

Fig. 3 is a vertical sectional view substantially on the line 3—3 of Fig. 1 showing the 40 pivotal construction for supporting the burner.

Fig. 4 is a vertical view, partly in section, on the line 4—4 of Fig. 3 showing the construction of the swinging joint between 45 the pipe which supports the oil supply tank and the oil supply pipe which supports the burner, for permitting only the burner to be moved outward or inward without disturbing the oil supply tank.

Referring to the drawings in detail:

1 designates the casing in which the water heating element is placed, 2 the door of the casing which is shown in open position. 3 is the burner proper, 4 the oil supply tank 55 and 5 is the water heating element of any suitable type having the inlet and discharge

pipe connections 5¹ and 5². 6 is a plate or platform for supporting the oil burner and the oil supply tank, and this plate is mounted on a standard 6^a. This plate is formed with a T-shaped groove 7 in which is located a correspondingly shaped pin or bolt 8 which is attached to a collar 9 that surrounds the oil supply pipe 10. Attached to the pipe 10 is a second collar 11 which is pivotally mounted on the plate 6 as indicated at 12. The pipe 10 leads to the oil supply tank 4 as indicated at 13. The burner 3 is supported on the pipe 10 and swings or turns about the pivotal center 12 when the burner is drawn outward away from the lower end of the heater element 5 as indicated in Fig. 2 by the dotted line position 3'. This enables the user of the heater to readily clean the burner 3 and the water heating element 5.

Referring to the modification shown in Figs. 3 and 4 the oil supply tank 4 is connected to the plate 6 through the medium of the pipe 14. 15 designates a member that is formed with a square or rectangular portion 16 which fits into a square shaped socket or recess 17 in the plate 6. 18 designates a stem integral with the part 16 that passes through an opening in the plate 6 and 19 is a nut for securing the part 15 to the plate 6. The upper end of the part 15 is formed with a conical shaped portion 20. Located on this conical shaped portion is the member 21 which is secured to the part 20 by means of the washer 22 and the screw 23. The part 21 is attached by means of the threads 24 to the oil supply pipe 10 which supplies oil to the burner 3. The pipe 10 in this construction is supported by means of the post or part 25 having the T-shaped part 8 as before which is located in the correspondingly shaped groove 7. This portion of the invention is the same as that described in connection with Figs. 1 and 2 but it differs from that construction in that the oil supply tank 4 is fixedly secured to the plate 6 instead of turning thereon and the pipe 10 moves with the burner 3. The advantage of this construction is that the water heater and tank 4 may be located close to a partition or wall and yet at the same time permit the burner 3 to be swung outwardly away from the casing. The parts 15, 20, 21 and 25 form a swinging joint with an oil passageway through these parts as indicated at 27.

It will be observed that the end of the pipe 14 is attached to and supported on the plate 6 through the medium of the part 15 previously referred to.

5. What I claim is:

1. In a burner, a burner element, a bearing plate for supporting the burner, said plate having an arc-shaped groove therein and an opening concentric with said groove,
- 10 an oil supply pipe on which the burner element is mounted, pivotally secured in the opening in the bearing plate, and a support for the burner element secured to the oil supply pipe and disposed in the arc-shaped groove.
- 15 2. In a burner for water heaters, a burner element, a plate having an arcuate groove therein T-shaped in cross section, an oil supply tank, an oil supply pipe in communication with the oil supply tank and pivotally connected to the plate, the burner element being mounted on said pipe, and a guide member secured to the pipe and adapted to traverse the arcuate groove the center of
- 20 25 which coincides with the pivotal connection of the oil supply pipe with the plate.
3. In a burner, a bearing plate, an oil supply tank, a pipe pivotally connected to the plate, a conduit placing the pipe in communication with the supply tank, said plate having an arc shaped groove, a burner on the pipe movable with the latter about the pivotal connection of the pipe, and a guide member partially supporting the pipe and movable in said arc shaped groove.
- 30 35 4. In a burner, a supporting plate having an arc shaped groove therein, an oil supply tank, an oil supply pipe for supporting the tank and having one of its ends connected to the plate, a second oil supply pipe pivotally connected to the end of the first mentioned oil supply pipe, an oil burner mounted on the second oil supply pipe, and a member on said burner for engaging the arc

shaped groove in the plate to support and 45 guide the burner.

5. In combination, an outer casing, an element to be heated therein, a burner below said element, means for pivotally supporting the burner with relation to the casing and 50 said element, said means including a plate secured to the casing and formed with an arc-shaped groove therein, and a part connected to the burner and movable in the groove for guiding and supporting the 55 burner while the latter is moved into or out of said casing.

6. A supporting device for a burner for water heaters, comprising in combination, a plate formed with an arc shaped groove, 60 a member pivotally connected to the plate and on which the burner is mounted, a part on the pivotally connected member for supporting the burner, said part being movable in the arc shaped groove of the plate to permit the burner to be swung under or away from the water heater.

7. A supporting plate for burners, said plate having an arcuate groove therein and an opening concentric therewith, said opening adapted to pivotally receive an oil supply pipe on which a burner is mounted, the arcuate groove adapted to receive a guide member for supporting and guiding the oil supply pipe and the burner. 75

8. In combination a casing, a water heater mounted in the casing, a supporting plate extending into the casing, a pipe pivotally mounted on the supporting plate, a burner carried by the pipe and adapted to be moved 80 with the pipe into or out of the casing, the burner when in the casing occupying a position beneath the water heater, said plate having an arc shaped groove, a supporting element for the burner connected to the pipe 85 and movable in the groove, and means for supplying oil to said pipe.

PETER S. SINCLAIR.
